UNITED STATES PATENT OFFICE.

ARTHUR WILLIAM WALL, OF SHELDON, NEAR BIRMINGHAM, ENGLAND, ASSIGNEE
OF THREE-FOURTHS TO JOHN WHITE, JR., OF BOULTON ROAD, HANDSWORTH,
BIRMINGHAM, ENGLAND.

INTERNAL-COMBUSTION ENGINE.

Application filed August 8, 1919. Serial No. 316,193.

To all whom it may concern:

Be it known that I, ARTHUR WILLIAM WALL, a subject of the Kingdom of Great Britain, residing at "The Laurels," Lyndon End, Sheldon, near Birmingham, in the county of Warwick, England, have invented certain new and useful Improvements in or Relating to Internal-Combustion Engines, of which the following is a specification.

10 This invention comprises certain improvements in or relating to internal-combustion engines, particularly of the two-stroke cycle type.

The present invention comprehends an internal-combustion engine having slide valve controlled inlet and exhaust, and having the piston adapted to slide over the exhaust port or ports; by this arrangement the exhaust port or ports are adapted during the 20 primary or any appropriate part of the explosion stroke to be protected from the ignited fluid by the piston. The expression "slide valve" is to be construed herein as excluding the engine piston itself, but as 25 including a valve which slides around the cylinder wall. Advantageously the piston is adapted also to slide over the inlet port or ports. In this arrangement the inlet and the exhaust ports are preferably situated 30 so that they are in the vicinity of the piston at bottom dead centre and so that the inlet port or ports are then between the exhaust port or ports and the piston.

The present invention further comprehends a two-stroke cycle internal-combustion engine in which the piston is adapted to slide over the ports admitting to the explosion space as well as the exhaust ports, and in which multiple inlet and exhaust 40 ports are located symmetrically around the cylinder, the exhaust ports being located further than the inlet ports from the end face of the piston when the latter is at bottom dead centre. By this arrangement of 45 ports improved power and efficiency are obtained.

This arrangement may or may not be combined with slide valve control of either inlet or exhaust or both.

50 The present invention further comprehends in an internal-combustion engine a slide valve arrangement comprising a sleeve or segment moving, preferably rotating, relatively to the cylinder at a comparably slow

speed and having a number of inlet and a 55 number of exhaust ports with corresponding openings in a fixed part of the cylinder adapted to register with the ports in the sleeve. These ports are situated in the part of the cylinder in the vicinity of the piston 60 at bottom dead centre. The ports in the sleeve register with the ports in the cylinder on two or more occasions in the course of a complete revolution of the crank but are closed by the piston except on one of these 65 occasions, namely, when it is at the end of the power stroke. By this means a sufficiently large valve opening is obtained and controlled and by a comparatively slowly moving sleeve or segment. 70

The present invention furthermore comprehends in an internal-combustion engine of the two-stroke cycle type, the utilization of a slide valve which controls the ingress to the precompression chamber, the transfer 75 passage, and the exhaust.

The slide valve may be located between the piston and the stationary cylinder wall, or an additional stationary wall may be located between the slide valve and the piston. 80

In order that this invention may be clearly understood and readily carried into practice, reference may be had to the appended explanatory two sheets of drawings, upon which:—

85 Figure 1 illustrates in sectional elevation an embodiment of the present invention, the plane of section being on line 1—2 of Figure 2.

Figure 2 illustrates in sectional plan, the 90 arrangement shown in Figure 1, the plane of section being on line 3—4 of the figure last mentioned.

Figure 3 illustrates in sectional plan the 95 arrangement shown in Figure 1, the plane of section being on line 5—6 of the figure last mentioned.

Figure 4 is a crank diagram indicating one suitable timing which may be employed in the engine shown in Figures 1, 2 and 3. 100

In a convenient embodiment of the present invention, as illustrated in the drawing, *a* represents the piston, which in Figure 1 is illustrated at the bottom of the stroke; *b* is the cylinder, *c* is a rotating sleeve 105 located externally of the wall *b*, *d* is a stationary liner located externally of the sleeve valve *c*, and *e* is a housing which is assem-

bled in half sections around the parts thus far enumerated. The housing *e* rotatably carries a worm wheel *f* which is driven in any suitable manner; this worm wheel *f* is in mesh with the sleeve valve *c* and adapted 5 appropriately to rotate the latter. In the example shown the sleeve *c* rotates once for every six revolutions of the crankshaft.

Formed in the housing *e* is an inlet port 10 *g* which communicates with an annular channel *h* encircling the liner *d*. In the liner *d* a series of symmetrically arranged ports *i* Fig. 2 are provided adapted to register with ports *j* provided in the sleeve valve 15 *c*. When these ports are in register, the inlet *g* is in communication with the interior of the crank chamber by way successively of the annular space *k* within the valve *c*, the openings *l* in the cylinder wall *b* and the 20 openings *m* in the piston *a*.

n is an annular space located externally of the sleeve valve, and which is in communication with the space *k* by a multiplicity of openings *o*. The upper extremity of 25 this space *n* is adapted to be placed in communication by the sleeve valve *c* with the explosion space *p*. For this purpose the sleeve valve *c* is formed with a series of symmetrically arranged openings *q* adapted 30 to register with a series of symmetrically arranged openings *r* in the cylinder wall *b*. The openings *q* and *r* register four times during a complete revolution of the crank but are closed by the piston on three of these 35 occasions. The fourth respective registration takes place at the end of the power stroke, when the ports have been uncovered by the piston and at a time when the channel *k*, *l*, *m* is not in communication with the inlet *g*, so that a transfer of the fluid from 40 the crank chamber to the explosion space is obtained.

Ports *s* Fig. 3 are also provided in the sleeve valve *c* and adapted at an appropriate 45 time to register with ports *t* provided in the cylinder wall. This registration takes place twice, once inoperatively, the openings being closed by the piston, and once at the end of the power stroke after the ports have 50 been uncovered by the piston, when the explosion space *p* is placed in communication with the annular space *u* and ultimately with the exhaust passages *v*.

A suitable crank diagram is indicated at 55 Figure 4, but the timing of the ports may obviously be considerably modified in this embodiment. In this diagram *w* represents the position of closing of the inlet, *x* the position of opening of the exhaust, *z* the 60 position of opening of the transfer passage, *y* the position of closing of the transfer passage, and also the position of opening of the inlet, and *8* the position of closing of the exhaust.

65 From Figure 1 it will be noted that both

the ingress and exhaust ports to and from the explosion space *p* are located in such a position that the piston completes a substantial part of its stroke before the exhaust ports are uncovered.

70 In the embodiment illustrated a rotary annular sleeve valve is employed, but, alternatively, we may employ an annular or segmental sleeve valve having other appropriate movement, such as a longitudinal 75 one, a helical one, or a combination of rotary and longitudinal movements.

What I claim as my invention and desire to secure by Letters Patent is:—

1. An internal combustion engine, having a cylinder provided with a plurality of inlet openings and a plurality of outlet openings, the inlet and outlet openings being located at different levels, a piston in said cylinder, a multiple ported sleeve 85 slideable on said cylinder and adapted in each cycle of movement of the piston to bring its ports into repeated registration with some of said outlet openings, the passage of gases through said ports and outlet openings when they are in register being repeatedly obstructed by said piston in each cycle of movement and being freed only when the piston is near bottom dead center, and means for imparting movement to said 95 sleeve.

2. An internal combustion engine, having a cylinder provided with a group of inlet and a group of outlet openings, the inlet and outlet openings being located at different levels, a piston in said cylinder, a multiple ported slideable sleeve on said cylinder and adapted in each cycle of movement of the piston to bring its ports into repeated registration with a group of said openings, the passage of gases through said ports and openings when they are in register being repeatedly obstructed by said piston in each cycle of movement and being freed only when the piston is near bottom dead 100 center, and means for imparting unidirectional movement to said sleeve.

3. An internal combustion engine, having a cylinder provided with a plurality of inlet openings and a plurality of outlet openings, 115 the inlet and outlet openings being located at different levels, a multiple ported sleeve in frictional engagement with a portion of said cylinder and adapted in each cycle of movement of the piston to bring its ports into repeated registration with said outlet openings, the passage of combustion gases through said ports and openings when they are in register being repeatedly obstructed by said piston in each cycle of movement 120 and being freed only when the piston is near bottom dead center, and means for rotating said sleeve.

4. An internal combustion engine, having a cylinder provided with a group of inlet 125

- openings and a group of outlet openings, the inlet openings and outlet openings being located at different levels and being uniformly distributed circumferentially of 5 the cylinder, a piston in said cylinder, a sleeve having ports uniformly distributed and circumferentially arranged thereon, the sleeve being slideable on said cylinder and being adapted in each cycle of movement 10 of the piston to bring its ports into repeated registration with said inlet and outlet openings respectively, the passage of gases through said ports and openings when they are in register being repeatedly obstructed 15 by said piston in each cycle of movement and all of the openings and ports of one of said groups being freed only when the piston is near bottom dead center, and means for imparting movement to said sleeve.
- 20 5. An internal combustion engine, having a cylinder provided with a plurality of inlet openings and a plurality of outlet openings, the inlet openings being located at a level different from the outlet openings, the inlet openings being uniformly 25 distributed circumferentially of the cylinder, the outlet openings being circumferentially and uniformly distributed on the cylinder, the arrangement of said outlet openings be-
- ing, however, different from that of the 30 inlet openings, a multiple ported sleeve slideable on said cylinder and provided with ports adapted to register repeatedly in each cycle of movement with all of the outlet openings in the cylinder, the passage of 35 gases through said ports and outlet openings when they are in register being repeatedly obstructed by said piston in each cycle of movement and all of the said ports and outlet openings being freed only when 40 the piston is near bottom dead center, and means for imparting movement to said sleeve.
6. An internal combustion engine, having a cylinder provided with circumferentially 45 distributed outlet openings and inlet openings, a piston, a multiple ported sleeve in said cylinder, and means movable in predetermined fixed relation to the movements of said piston for admitting fuel into and 50 discharging gases from said cylinder simultaneously through all of said inlet openings and all of said outlet openings respectively.

In witness whereof I have hereunto set 55 my hand.

ARTHUR WILLIAM WALL.
